Des. 216,875
Patented Mar. 17, 1970

216,875

ARMORED MOTOR VEHICLE

Russell E. Bauer, Grosse Pointe, Mich., assignor to Bauer
Ordnance Company, Warren, Mich., a corporation of
Michigan

Filed Feb. 19, 1969, Ser. No. 15,844

Term of patent 14 years

Int. Cl. D12—13

U.S. Cl. D14—3

FIG. 1

FIG. 2

FIG. 3

FIG. 4

FIG. 5

FIG. 6

FIG. 1 is a front perspective view of my novel, ornamental design for an armored motor vehicle;

FIG. 2 is a rear perspective view thereof;

FIG. 3 is a front elevation view thereof;

FIG. 4 is a right side elevation view thereof;

FIG. 5 is a left side elevation view thereof; and

FIG. 6 is a rear elevation view thereof.

The dominant features of my design reside in the portions shown in full line.

I claim:

The ornamental design for an armored motor vehicle, as shown and described.
